CLAIM

The ornamental design for a support for a fluid collection pouch, as shown and described.

DESCRIPTION

FIG. 1 is a front top side perspective view of a support for a fluid collection pouch showing our new design; FIG. 2 is a front elevational view thereof, the rear elevational view thereof being similar except for the plain surface;

FIG. 3 is a right side elevational view thereof in section; and

FIG. 4 is a right side elevational view thereof, the left side elevational view and top and bottom plan views being identical.

The broken lines in each of the figures represent a fluid collection pouch and are shown for illustrative purposes only and form no part of the claimed design.
